UNITED STATES PATENT OFFICE.

FRANÇOIS JULES CHAPSAL, OF PARIS, AND ALFRED LOUIS EMILE SAILLOT, OF LA GARENNE-COLOMBES, FRANCE.

PNEUMATIC BRAKE.

1,230,277.

Specification of Letters Patent. Patented June 19, 1917.

Application filed February 27, 1914. Serial No. 821,375.

To all whom it may concern:

Be it known that we, FRANÇOIS JULES CHAPSAL and ALFRED LOUIS EMILE SAILLOT, citizens of the French Republic, residing at 5 Paris, and La Garenne-Colombes, Department of the Seine, in France, have invented certain new and useful Improvements in or Relating to Pneumatic Brakes; and we do hereby declare the following to be a full, 10 clear, and exact description of the invention, such as will enable others skilled in the art to which it appertains to make and use the same.

This invention relates to brake application accelerators of the kind described in 15 the United States Patent, No. 929,551, dated July 27, 1909. These improvements relate to new means for controlling the charging and exhausting of the chambers and consist in:—

1. Combining the brake application accelerating valve of the lower chamber, with an automatic interrupter of rapid action constituted by a piston valve interposed be- 25 tween the distributer and the exhaust ori- fice for the air of the train pipe, the slide valve and its facing rendering this double acting accelerator applicable as a double acting distributer accelerator to compressed 30 air brakes having an auxiliary reservoir, the regulating reservoir being replaced in this case by a special air reservoir for refilling purposes having a volume as great as de- sired, while the auxiliary reservoir is con- 35 nected directly with the upper chamber of the double acting accelerator converted into a distributing accelerator; the complete graduation during the application and re- lease of the brakes with a proportional re- 40 filling of the auxiliary reservoir at each re- lease being thus carried into effect, while the same apparatus may be used as a double acting accelerator of a compressed air brake having a single chamber adapted to be grad- 45 uated during the release and application of the brakes by closing with a plug the orifice of communication with the atmosphere and by leaving open to the atmosphere the circular groove which terminates at the brake 50 cylinder, the regulating reservoir being then connected with the circular groove com- municating with the main conduit through the medium of the piston of the antifluc- tuator, the distributer being connected

through the medium of a pipe opening into 55 the upper chamber of the accelerator.

2. In modifying the distributer described in the specification of the British Patent of addition No. 4485/14 filed on the 20th February 1914, so as to control the automatic 60 interrupter for the rapid action as has been described hereinbefore and, moreover, in rendering the accelerator thus improved, ap- plicable to compressed air brakes with an auxiliary reservoir, the auxiliary reservoir 65 having been replaced by a special air reser- voir so-called a "re-filling" reservoir of a volume as great as desired, while the aux- 70 illiary reservoir is connected directly with the upper chamber of the double acting ac- celerator converted into a distributer.

In the accompanying drawing:—

Figure 1 illustrates a section through the modified double acting accelerator, the anti- 75 fluctuator, the automatic interrupter, the braking accelerating valve, the valve being in the central position of the movable mem- brane which controls them.

Fig. 2 shows the position occupied by this valve when the movable membrane is raised 80 at the end of the stroke.

Fig. 3 illustrates the position of the same valve corresponding to the complete lower- 85 ing of the movable membrane.

The accelerator comprises two chambers I and S separated by the movable membrane M which may be replaced by a piston. The main or train conduit opens at 1 into the accelerator and the air of this conduit passes:—

On the one hand, through the conduits 2 and 3 into the lower chamber I, raising thus the movable membrane M which brings the valve T to the end of its stroke into the po- 90 sition shown in Fig. 2.

On the other hand, through the channels 4 and 5 under the valve of the antifluctuator 6. If this air is supplied slowly under this valve, the spring R' remains completely ex- 100 tended as illustrated in Fig. 1 and allows the train or main conduit air to pass above the valve 6, through the conduit 7 and the ports 8 and 9 whence it subsequently passes through the conduit 10 into the conduit 11 which through the medium of the circular 105 conduit 12—12 brings it to the pipe R connected with the regulator reservoir. The air passing through the conduit 11, 12 also

passes through the port 13 uncovered by the valve T (see Fig. 2) into the upper chamber S communicating directly with the branch B leading to the brake distributor so that the 5 braking apparatus are normally loaded. If the supply of air underneath the piston 6 is, however, sudden as may take place at the head of the train the spring R' is compressed and the air from the train conduit can pass into the space above the valve 6 through the throttled port 9 only as long as 10 the difference in pressures exerted on the two faces of the valve, is sufficient to prevent a communication between the port 8 and the space above the valve 6 through the medium 15 of the compressed spring R'. The charging of the braking apparatus is therefore slowed down in the first portion of the train thus facilitating the propagation to the rear of the train of the filling air wave of the train conduit so that the charging of the brakes of the second portion of the train is accelerated because the pistons 6 in this second 20 portion are not sufficiently compressed to hide the port 8 owing to the reduced speed of the supply of air, contrarily to what takes places in the first portion of the train.

The modified double acting accelerator operates in the following manner:

30 Application of the brakes.

If a sufficient reduction in pressure is effected in the main or train conduit, in order to apply the brakes, the valve 6 will 35 soon descend on to its seat 14 and entirely cuts off this conduit from the upper chamber S and the conduits opening into the regulating reservoir R while the movable membrane M descends carrying therewith 40 the valve T which closes the orifice 13 and opens subsequently the braking accelerating valve 15 retained upon its seat R² loaded in such a manner as to balance the maximum pressure of the train conduit acting on 45 this valve. The air of the main conduit which escapes through this braking accelerating valve is therefore suddenly expanded through the orifice 16 into the lower chamber 17 of the piston valve A which constitutes the automatic interrupter, whence 50 it is exhausted directly into the atmosphere through the orifice 18 the opening and closure of which are, as will be explained hereinafter, controlled by the automatic interrupter so that the reduction in pressure produced in the main conduit by the air which escapes through the accelerating valve should be limited to a predetermined maximum. The opening of the accelerating 55 valve increases the downward movement of the valve T which uncovers the port 19 placing the chamber S connected with the branch B leading to the distributor, in direct communication with the atmosphere 60 through the orifice 20 until the drop in 65

pressure resulting therefrom in this chamber and also in the branch, produces the movement in the opposite direction of the movable membrane and of the valve T, this movement being stopped when the upper edge of the valve closes again the port 19 (see Fig. 1); the valve T not being pushed back to the end of its stroke, the orifice 13 remains closed as well as the orifice 18 of the lower chamber of the automatic interrupter as will be seen hereinafter, and they remain in this condition until the maximum application of the brakes from the driver's valve by means of successive or continuous reductions in pressure which are rapidly so transmitted to the rear of the train because the main conduit remains completely cut off from the braking apparatus after the first application of the brakes until the first partial or complete release of the brakes reestablishes the rapid action by opening the accelerator valve 15, as will be described hereinafter.

The piston valve A which constitutes the interrupter for the rapid action, has, as shown in Fig. 1, its upper face connected at 21 to the port 22 of the valve facing through the medium of a conduit 23, 24, 21, so that during the release of the brakes (see Fig. 2) the valve places this face of the piston in direct communication with the atmosphere through the orifice 20 while during the application of the brakes (see Fig. 3) this upper face of the piston is placed in direct communication with the regulating reservoir. When the brakes are released, however, the piston valve A is maintained in the position shown in Fig. 1 by a spring R³ loaded in such a manner as to balance a pressure of air acting on the upper face of the piston, equal to the value of the maximum reduction in pressure in the main conduit fixed for the rapid action provoked by the escape of air from this conduit through the rapid application of the brakes, the piston valve A having its upper face subjected to the pressure of the air of the controlling reservoir which is invariable during the application of the brakes, remains in the elevated position as long as the loaded spring R³ balances the drop in pressure in the main or train pipe, and subsequently descends, closing the orifice 18 for the exhaust to the atmosphere, thus limiting the depression in the train conduit to the maximum fixed for the rapid action produced by the exhaust of this conduit through the accelerating valve, the additional application of the brakes being subsequently continued from the driver's valve until the brakes are fully on. The maximum reduction of pressure in the main conduit, due to the rapid action, is, therefore, independent of the number of vehicles of the train provided with braking members of the con- 130

tinuous brake. It follows therefrom that when during the graduation of the braking during the descent of long inclined stretches of road, slight leakages take place in the 5 main conduit, their only effect can be to produce a slight increase of the braking effort as the rapid action can not produce a fresh direct exhaust to the atmosphere of the air contained in the main conduit through the 10 medium of the accelerating valve.

Release of the brakes.

If in order to release partially or completely the brakes, the main conduit is 15 refilled, the valve 6 of the anti-fluctuator (see Fig. 1) remains, first of all, seated on its seat 14—14, as the pressure exerted on the upper face of this piston is equal to the pressure of the regulating reservoir which 20 remains invariable during the application of the brakes. It follows therefrom that the flexible membrane M is raised and pushed to the end of its stroke (see Fig. 2) effecting, first of all, the closure of the valve 15 for accelerating the application of the brakes, then the opening of the port 13 through which air from the controlling reservoir passes to the upper chamber S, and, therefore, to the branch leading to the distributor. The increase 25 of pressure which is a consequence thereof produces, at a certain moment, the movement of the movable membrane and of the valve T in the opposite direction, this movement stopping when the lower edge of 30 this valve closes again the port 13, the valve 15 remaining closed.

To each supply of air into the main conduit, a partial supply of air from the regulating reservoir corresponds therefore immediately 40 in the upper chamber S and in the branch leading to the distributor, giving rise to an increase of pressure slightly superior to that of the main conduit until the pressure on both faces of the movable 45 membrane are balanced. The refilling of the branch, and, therefore, the release of the brake, are graduated until the release of the brakes is complete corresponding to the moment when the controlling reservoir 50 is completely expanded into the upper chamber and into the branch. The additional filling of the main conduit has, therefore, for its effect to replace the brake members into the operative position (see Fig. 2) 55 as the operated movable membrane M is pushed to the end of its stroke.

We claim:

1. In an air-brake system for railway trains, the combination with the train pipe and an air reservoir, of an accelerator comprising a valve and means to open the same upon a reduction of pressure in the train pipe, and means to control the discharge of air from said valve to the atmosphere comprising a second valve, and a piston controlling the movement of said second valve, said piston being subject on one side during application of the brakes to the pressure of air in said reservoir and at the other side to the pressure of the air in the train pipe. 60

2. In an air-brake system for railway trains, the combination with the train pipe and an air reservoir, of an accelerator comprising a valve and means to open the same upon a reduction of pressure in the train 75 pipe, means to control the discharge of air from said valve to the atmosphere comprising a second valve, and a piston controlling the movement of said second valve, said piston being subject on one side during application of the brakes to the pressure of air in said reservoir and at the other side to the pressure of the air in the train pipe, means to supply air from the train pipe to said reservoir, and a valve to cut off communication between the train pipe and said reservoir when the pressure in the train pipe is reduced to a predetermined limit. 80

3. In an air-brake system for railway trains, the combination with the train pipe 90 and an air reservoir, of an accelerator comprising a valve and means to open the same upon a reduction of pressure in the train pipe, a second valve also operated by said means, means to control the discharge of air 95 from said first-named valve to the atmosphere comprising a third valve, and a piston controlling the movement of the same, said second valve serving to place one side of said piston in communication with said 100 reservoir upon a reduction of pressure in the train pipe and said piston being subject at its other side to the pressure of air in the train pipe.

In testimony whereof we affix our signatures, in presence of two witnesses.
